UNITED STATES PATENT OFFICE

WILLIAM T. HANCOCK, OF LONG BEACH, CALIFORNIA

CRACKING STILL

Application filed August 21, 1929. Serial No. 387,380.

This invention has reference to an improved form of still for the liquid phase cracking of hydrocarbon oils, and has for its principal object the provision of an apparatus whereby petroleum oils may be cracked to obtain maximum yields of distillate, preferably by the use of heating or cracking elements of the type comprising the subject matter of the patent No. 1,680,541, on Oil cracking still, issued August 14, 1928, to J. W. Hancock and myself. In the present type of still, the cracking stock is passed through one or more heating tubes, during which time it is heated to cracking temperature, and thereafter conducted to a reaction chamber where it is maintained under pressure for a length of time sufficient to complete the cracking reaction. I have found that by maintaining the liquid oil under pressure during its flow through the heating tubes, and by agitating the oil during heating and simultaneously scrubbing the tube walls to remove carbonaceous bodies deposited thereon, preferably by the mechanism described in the referred patent, high yields of cracked product are obtained and continuous operation over long periods of time is enabled by the provision of means for effectively removing from the system heavy residual materials.

The form of heating elements described in the referred patent may be characterized generally as comprising a mechanism whereby tarry or carbonaceous bodies formed during the cracking reaction, are prevented from depositing on the heating walls of the apparatus, these materials instead of being withdrawn continuously with the residue. The mechanism in its preferred form comprises an externally heated cylindrical tube within which a series of disks are mounted at angles on a longitudinal and rotatable central shaft. A plurality of metallic balls are confined between the disks and are adapted to be moved upon rotation of the shaft in such a manner that they roll over the lower portion of the tube wall and are elevated and dropped against the wall with hammering effect. The balls simultaneously are caused to move back and forth longitudinally

tudinally between the annularly arranged plates, and thus have both scrubbing and hammering action on the tube wall with the result that solid matter is prevented from depositing thereon, and instead kept in suspension in the residual liquid. During operations, the oil is fed into one end of the tube and in flowing therethrough is subjected to vaporization and cracking the heavy residual liquid being withdrawn at the opposite end of the tube.

I have found in accordance with the present invention that materially increased yields and efficiency in operation may be gained by the use of one or more of the described heating elements in combination with a reaction chamber, initial heating of the oil to high temperature and under pressure taking place in the heating units or tubes, and the cracking reaction carried to completion by maintaining the high temperature oil under pressure within the reaction chamber. By virtue of the particular arrangement of the heating units and the reaction chamber, provision is made whereby the heavy carbonaceous and residual materials precipitated within heating units and also in the reaction chamber, may be readily discharged from the system. Maintaining the reaction chamber under pressure serves also to maintain the oil in the heating tubes under pressure, and it may be stated that by heating and agitating the oil under pressure, cracking results to a materially greater degree than by merely allowing the oil to flow through the tube at substantially atmospheric pressure. As stated however, cracking to a final and maximum degree occurs upon maintaining the heated and partially cracked oil for a period of time in the reaction chamber.

The above characteristics and advantages of the invention as well as additional features will be understood most readily from the following detailed description, throughout which reference is had to the accompanying drawings, in which:

Fig. 1 is an elevation, partly in section of a preferred form of apparatus embodying the invention;

Fig. 2 is a plan view of the cracking still shown in Fig. 1;

Fig. 3 is an end elevation as viewed from the left of Fig. 2;

Fig. 4 is a fragmentary enlarged longitudinal section through one of the heating units; and

Fig. 5 is an enlarged cross section on line 5-5 of Fig. 1.

Referring to the drawings, the furnace 10 may be heated by any suitable means, for instance by the oil burner 11, the hot combustion gases being conducted upwardly and over the baffle wall 12, and thence downwardly into the flue 13. A plurality of heating units generally indicated at 14, and of which there may be any suitable number, four being shown as typical, are terminally supported in the end walls of the furnace. The oil comprising the cracking stock is delivered to the heating units through inlets 15a by way of header 15, to which oil is delivered from the supply line 17 by a pump 17a. The units 14 preferably are inclined somewhat as indicated, and at the lower ends of the units, outlet pipes 18 lead to a common header 19. Within each of the tubular shells 24 of the heating units is a rotatable and central shaft 20 carried in a bearing at 21 at the upper end of the unit, and at its opposite end by a bearing 22 which may, at the same time, constitute a stuffing box. This stuffing box is carried on the end of a pipe 23 of reduced diameter which projects beyond the lower end of the tube 24 outside the furnace, thereby enabling the stuffing box to be maintained at a comparatively lower temperature than that within the furnace. The feed oil delivered to the heating units through header 15 flows downwardly through the tubes 24, during which time the oil is heated and subjected to cracking to a considerable degree. The discharge from the heating tubes 24 occurs through outlets 18, the header 19, and into the reaction chamber 26 by way of pipe 27.

The central longitudinal shaft 20 carries a plurality of disks 30 set in planes making a somewhat acute angle with the shaft as shown in Fig. 4, the disks being of such diameter that their peripheries are spaced slightly from the tube wall. Between adjacent disks a number of balls 31 is confined, preferably a large enough number to make two rows of balls between adjacent disks. By using balls of say one inch diameter, with three in each row between adjacent disks, the distance between the disks may be slightly more than three inches. The distance between ball centers being thus something more than one inch, the disks 30 preferably are set at an angle such that upon rotation, they will impart to the balls resting in a row at the bottom wall of the shell 24,

a longitudinal movement somewhat in excess of the distance of adjacent ball centers. Between the disks are arranged the radial plates 32 which act during rotation of the shaft, to carry the balls around the inside tube. The inner edges 32a of these plates have suitable clearance from the shaft 20, thereby providing an additional space for passages of liquid or vapor from one side of the plates to the other. Likewise the outer edges 32b do not quite contact with the tube wall, these edges preferably being inside the peripheries of the disks 30 which in turn are slightly spaced from the tube as indicated at 33.

The longitudinal ball actuating shafts 20 may be rotated by any suitable means, and as a typical form of drive, I have shown the shafts provided at their lower ends 20a, projecting through the stuffing boxes 22, with gears 35 meshing with gears 36 on shaft 37 which is driven by chains 38 extending over sprockets 39 on shafts 37, and sprockets 40 on the main drive shaft 41, the latter in turn being rotated by suitable drive means, for instance a motor M. Thus it will be noted that the shafts 20 and disks 30 are simultaneously rotated and at the same speed by means of the described driving mechanism.

The operation of the parts comprising the individual heating elements will be readily understood upon inspection of Figs. 4 and 5. The unvaporized liquid in flowing from the upper toward the lower ends of the tubes 24 passes around the edge of each disk 30 and in a comparatively thin stream directly against the heated tube wall, and thus is periodically and repeatedly subjected to effective heating. And also whatever gases and vapors are liberated are likewise caused to repeatedly flow around the edges of the disks and thus come into intimate contact with the heating tube. At the same time, both the vapor and liquid are constantly moving in circuitous paths and are constantly intermingled, so that these phases come into repeated contact with each other and also into repeated contact with the tube wall. It will be apparent that rotation of the balls likewise is effective in causing intermingling of the liquid and vapor, as well as performing the particular functions which will now be described.

It will be readily seen that upon relative slow rotation of the shaft 20, a row of balls that may be temporarily resting on the bottom of the tube will be picked up by a plate 32 and elevated in contact with the tube wall until they reach a position somewhat as shown in full lines in the position A in Fig. 5. Upon reaching this position, the balls roll down plate 32 and, usually striking shaft 20, bounce off and strike the opposite wall of the tube at such a position as shown

at B, thence dropping downward to the position C. Thereafter the rotation of plate 32 allows the balls to roll down the tube wall to the lowermost position D, where the balls remain until picked up by the next plate. During this operation, the balls are moved back and forth longitudinally of the tube by virtue of the disks 30 being set at angles as previously mentioned. By all

10 these combined actions, the balls are caused to scrub the inner surface of the tube thoroughly, and particularly the lower part in which the heavy residual and carbonaceous bodies would otherwise collect, and also to

15 continuously hammer the tube so as to loosen any deposit which may become attached to it. The heavy particles thus are kept free and agitated in the liquid, and are carried by the liquid to the lower outlet end of the

20 tube.

The hot liquid from the cracking units delivered to the reaction chamber 26 is maintained at a constant predetermined level L by suitable means, for instance a float 25 controlled valve 45 in the reaction chamber outlet line 46. The residual liquid from the chamber discharged through line 46, is combined with the feed in line 17 and returned to the tubes 14 to be subjected to further 30 heating and cracking. The vapors formed during the flow of oil through the tubes as well as those liberated from the liquid body 47 in the reaction chamber, are conducted through the vapor line 48 to the dephlegmator 49, the undesirable heavy fractions in the vapor and entrained particles preferably being absorbed in a portion of the feed oil introduced through line 50 at the top of the dephlegmator, and returned through line 51 35 to the feed in line 17. Provision is made for controllably maintaining a high pressure, preferably between 100 and 200 pounds per sq. in., within the reaction chamber and therefore in the cracking tubes, by means 40 of the pressure regulating valve 52 in the vapor line 48. Under certain conditions it may be desirable to provide an additional pressure regulating valve 53 in the reaction chamber inlet line 27, whereby a comparatively 45 higher pressure may be maintained in the cracking tubes to prevent excessive vaporization therein, the reaction chamber pressure being comparatively lower in this case. Generally however it is preferred to 50 maintain substantially the same pressure in both the cracking tubes and reaction chamber, and to regulate the pressure by the single valve 52.

Due to the heating of the oil to cracking 55 temperatures in flowing through the tubes 14, heavy carbonaceous materials are precipitated as a result of the cracking reaction, and as previously mentioned, these bodies are carried in the liquid to the lower ends 24a 60 of the tubes. In order to effectively remove

the tarry materials at this point, I provide a purge line 55 in the bottom of the lower ends of each of the tubes, and by periodically opening valves 56 in the purge line, the undesirable heavy materials are completely forced out of the tubes. Preferably 70 drum 26a forming the reaction chamber is also inclined to such an extent as to cause carbonaceous bodies precipitated therein to settle out of the liquid at 26b in the lower end bottom of the still. As in the previous instance, these materials are periodically discharged from the chamber by opening valve 58 in the blow-off or purge line 55.

Preferably the capacity of the reaction chamber is large in comparison with the rate of flow of the stock through the cracking tubes, and consequently the heated liquid is retained in the chamber a considerable length of time in order to enable the cracking reaction to be carried out to the highest possible degree. As a typical example in the operation of the still using Diesel as the charging stock, the oil may be heated and delivered into the reaction chamber at a 90 temperature preferably between 600 and 900° F., the amount of product gasoline, based on the charging stock, obtained upon final rectification and condensation of the vapors, being in the neighborhood of 50%. 95

I claim:

1. In a cracking still, a furnace, a plurality of exteriorly heated inclined tubes in said furnace each tube having a liquid inlet at its upper end and a heated liquid and vapor outlet at its lower end, said tubes being inclined to cause carbonaceous solids therein to settle toward the lower ends of the tubes, a rotatable shaft extending centrally and longitudinally through the tube, 100 a tube of reduced diameter extending centrally from one end of the tube, a stuffing box at the end of said smaller tube, and the shaft projecting out through said stuffing box, a plurality of ball confining disks set rigidly on said shaft and longitudinally spaced from each other, said disks lying in parallel planes making acute angles with the shaft, pairs of ball carrying plates set between adjacent disks in a radial longitudinal plane, the plates of each pair being at opposite sides of the shaft, the inner edges of the plates being spaced from the shaft and the outer edges of the plates and the peripheries of the disks being slightly 110 spaced from the tube walls, sets of free balls in the spaces between adjacent disks and at opposite sides of the pairs of plates; means for simultaneously driving said shafts at their projecting ends, an inclined reaction chamber above said tubes and into which heated liquid and vapor is discharged from the tubes through said outlets, means for controllably maintaining a high pressure in said tubes and the reaction chamber, 120 125 130

and valve controlled purge lines at the lower ends of the reaction chamber and the heating tubes.

2. In a cracking still, an inclined heating tube having a liquid inlet and an outlet at its opposite ends, a longitudinally rotatable central shaft extending therethrough, a plurality of longitudinally spaced ball confining disks mounted on said shaft with their peripheries close to the inner surface of the tube, free balls in the spaces between adjacent disks, and ball carrying plates situated between adjacent disks, said ball carrying plates being arranged in pairs between each two adjacent disks, the plates of each pair being substantially diametrically opposite each other, and there being two sets of said balls, one set at each of the opposite sides of said plates, a carbon residue purge line at the lower end of said heating tube, a reaction chamber above said tube, liquid and vapors being discharged into the chamber from the heating tube through said outlet, said reaction chamber being inclined to cause solid carbon precipitate to settle toward its lower end, a purge line at the lower end of said chamber, a line leading from said heating tube inlet into the reaction chamber, and means for controlling the pressure in said reaction chamber and in the heating tube.

3. In a cracking still, a plurality of inclined heating tubes arranged side by side, each of said tubes having a liquid inlet and outlet at its upper and lower ends respectively, a rotatable shaft extending longitudinally therethrough, free balls within the tube, and means on said shaft for engaging and agitating the balls; drive means for rotating the shafts, a reaction chamber above said tubes and into which heated liquid is discharged from the tubes through said outlets, said reaction chamber being inclined to cause solid carbon precipitate to settle toward its lower end, a valve controlled purge line at the lower end of the chamber, a manifold communicating with said liquid inlets to said heating tubes, a line leading from said manifold into the reaction chamber at a point above its lower end, and means for controllably maintaining pressure in said tubes and the reaction chamber.

4. In a cracking still, a plurality of inclined heating tubes, each of said tubes having a liquid inlet and outlet at its upper and lower ends respectively, a rotatable shaft extending longitudinally therethrough, free balls within the tube, and means on said shaft for engaging and agitating the balls; drive means for rotating the shafts, a reaction chamber above said tubes and into which heated liquid is discharged from the tubes through said outlets, said reaction chamber being inclined to cause solid carbon precipitate therein to settle toward one end of the

chamber, a valve controlled purge line at the lower end of said chamber, a line communicating with said chamber at a point above the bottom thereof and communicating with the inlet ends of said tubes, means for controllably maintaining a high pressure in said tubes and the reaction chamber, and valve controlled purge lines at the lower ends of the heating tubes.

In witness that I claim the foregoing I have hereunto subscribed my name this 24th day of July, 1929.

WILLIAM T. HANCOCK.
